(57) **CLAIM**

The ornamental design for a scooter, as shown and described.

DESCRIPTION

FIG. 1 is a top plan view of the scooter showing my design in a collapsed configuration;

FIG. 2 is a top plan view thereof in an extended configuration;

FIG. 3 is a side elevation view thereof in the collapsed configuration;

FIG. 4 is a side elevation view thereof in the extended configuration;

FIG. 5 is a front perspective view thereof in the collapsed configuration;

FIG. 6 is a front perspective thereof in the extended configuration;

FIG. 7 is an opposite side elevation view thereof in the collapsed configuration;

FIG. 8 is an opposite side elevation view thereof in the extended configuration;

FIG. 9 is a back elevation view thereof in the collapsed configuration;

FIG. 10 is a back elevation view thereof in the extended configuration;

FIG. 11 is a bottom plan view thereof in the collapsed configuration;

FIG. 12 is a bottom plan view thereof in the extended configuration;

FIG. 13 is a front elevation view thereof in the collapsed configuration; and,

FIG. 14 is a front elevation view thereof in the extended configuration.

The extended configuration corresponds to the shaft and handles unfolded from the foot board of the scooter. The collapsed configuration corresponds to the shaft and handles folded to the foot board of the scooter.
